UNITED STATES PATENT OFFICE.

SAMUEL BAUM, OF LITTLE FALLS, NEW YORK.

SLED.

SPECIFICATION forming part of Letters Patent No. 314,217, dated March 24, 1885.

Application filed January 30, 1885. (No model.)

To all whom it may concern:

Be it known that I, SAMUEL BAUM, a citizen of the United States, residing at Little Falls, in the county of Herkimer and State of New York, have invented a new and useful Improvement in Sleigh-Runners, of which the following is a specification, reference being had to the accompanying drawings.

My invention relates to an improvement in 10 sleighs adapted more especially for what are known as "bob-sleighs"; and it has for its object to provide improved means for the attachment of a steel shoe to the runner, to so form the runner that it will serve as a brace 15 for the cross-piece or sand-board connecting the runners, and to so form the runner that it will brace the raves and protect the same.

A further object of the invention is to provide a novel construction of braces for the 20 different parts and to provide a sleigh which shall be simple in its construction and strong and durable.

In the drawings, Figure 1 is a perspective view of one truck of a bob-sleigh. Fig. 2 is a 25 longitudinal vertical section on the line xx of Fig. 1, and Fig. 3 is a transverse vertical section.

In the accompanying drawings, in which like letters of reference indicate corresponding 30 parts in all the figures, A represents one truck of a sleigh, the same being constructed as follows:

B B' represent the runners, and as they are both of the same construction a description of 35 one of them it is thought will be sufficient. The runner B is provided upon its underside or face with a longitudinally-disposed groove, a , which extends its entire bearing length.

C represents a shoe, which is preferably of 40 steel. The said shoe C is provided on its upper side with an upwardly-extending rib, b , which rib is adapted to fit the groove in the runner B, and be secured therein by bolting or riveting.

45 The runners B B' have a gradual curve upward at their forward ends, and at a point about on a line with the raves C' the said runners are bent rearwardly, as shown. The said rearwardly-bent ends of the runners are 50 somewhat wider than the bottom or body por-

tion of the same, and are provided with downwardly-extending flanges c , which bear against the side edges of the raves. It will thus be seen that the upper faces and the sides of the raves are inclosed and protected for about half 55 their length by the construction of runner shown; and it will be seen that, if so desired, the runners might be extended so as to inclose the raves their whole length.

The raves are connected upon their upper 60 sides at a point adjacent to the rear ends of the flanged portions of the runners by a connecting or sand board, D, and the rear ends of the runners are extended and turned forwardly and upwardly, as shown at d , and are 65 then turned inwardly and secured to the under side of the sand-board, thus bracing and supporting the same.

Formed integral with or secured to the extended ends of the runners are curved braces 70 e , which connect the runners and the under sides of the raves at their rear ends, thus bracing and firmly supporting the same.

E represents a brace, having a looped end, 75 which is secured to the under side of the sand-board, the ends of said brace extending to the under sides of the raves, near the forward ends thereof, at which point they are secured, preferably by screws passing through eyes in the same.

Secured to the upper sides of the runners, 80 on a line with the ends of the sand-board, are braces E' , which are formed at their upper ends with branch arms f , which, as shown, are secured to the under sides of the raves and 85 the sand-board, two of the arms of said braces being secured to the raves, while the inwardly-extending arms are secured to the sand-board.

F F represent braces which are secured to the raves at g , from which point they extend 90 inwardly, and are secured to the under side of the sand-board, as shown at h . The lower ends of these braces are split or divided, and form two arms, i , which are secured to the upper sides of the runners, near the forward 95 ends thereof.

It will be seen that, if desired, the upper ends of the runners might extend the entire length of the raves upon the under side thereof and be welded to the rear ends of the run- 100

ners. In this case the extended ends of the runners would have flanges projecting upwardly instead of downwardly.

It will also be seen that by the construction shown and described a sleigh is provided which is thoroughly strong, and one which will last a long time and not be likely to need repairs.

By constructing the runners with the grooves 10 to receive the tongues of the shoes it will be seen that increased space is afforded in which to countersink the securing-bolts.

Having fully described my invention, what I claim as new, and desire to secure by Letters 15 Patent, is—

1. In a sleigh, the combination, with runners having their forward ends extended and bent rearwardly and formed with flanges, of raves adapted to fit said flanges, substantially 20 as set forth.

2. In a sleigh, the combination, with the runners having grooves upon their undersides, of shoes having ribs or tongues to fit the same, the ends of said runners being formed with 25 downwardly-extending flanges, and raves adapted to be fitted between said flanges, substantially as set forth.

3. In a sleigh, the combination, with the runners having their rear ends bent forwardly 30 and inwardly and raves mounted above the runners, of a sand-board secured to the forwardly and inwardly bent ends of the runners and to the raves, and shoes having ribs or tongues to fit grooves in the under faces of the 35 runners, substantially as set forth.

4. In a sleigh, the combination, with the runners having the forwardly and inwardly extending rear ends, raves mounted above and connected with said runners, and a sand-board connecting said raves, of braces connecting 40 the forwardly and inwardly extending rear ends of the runners and the raves, as set forth.

5. In a sleigh, the combination, with the raves and runners supporting the same, of the sand-board and braces F, secured to the under side of the raves, bent inwardly and secured to the sand-board, their other ends being divided and secured to the runners, as shown and described.

6. A sled comprising in its construction 50 runners having grooves on their under faces, shoes having ribs to fit the same, the forward ends of the runners being flanged, turned back, and secured to the raves, the sand-board connecting the runners, said runners having their rear ends turned inwardly and forwardly and secured to the sand-board, braces e, connecting the rear ends of the runners and raves, and the braces F, connecting the raves, sand-board, and runners, substantially as set forth. 55

In testimony that I claim the foregoing as my own I have hereto affixed my signature in presence of two witnesses.

SAMUEL BAUM.
